The ornamental design for a transparent cylindrical container with beef jerky therein, as shown and described.

DESCRIPTION

FIG. 1 is a perspective view of a transparent cylindrical container with beef jerky therein embodying our new design;

FIG. 2 is a front elevational view thereof, all other sides being identical thereto, with portions of the wall being shown broken away for clarity of illustration;

FIG. 3 is a top plan view thereof; and,

FIG. 4 is a bottom plan view thereof.
